UNITED STATES PATENT OFFICE.

HADLEY F. FREEMAN, OF LAKEWOOD, OHIO, ASSIGNEE TO KELVINATOR CORPORATION
ON DETROIT, MICHIGAN, A CORPORATION OF DELAWARE.

REFRIGERATION.

Application filed January 8, 1925. Serial No. 93.

To all whom it may concern:

Be it known that I, HADLEY F. FREEMAN, a citizen of the United States of America, and a resident of Lakewood, in the county of Cuyahoga and State of Ohio, have invented certain new and useful Improvements in Refrigeration, of which the following is a full, clear, and exact description.

My invention relates to refrigeration and the principal object of my invention is to provide means adapted to indicate exteriorly of a refrigerator the temperature existing within the refrigerator and to perform this result accurately and without interfering with or decreasing the efficiency of the refrigeration. In the drawings accompanying this specification and forming a part thereof I have shown, for purposes of illustration, one form which my invention may assume. In these drawings:

Figure 1 is a front elevation of a section of refrigerator wall showing the application of this illustrative embodiment of my invention, while—

Figure 2 is a section on the line 2—2 of Figure 1.

The device herein shown includes a thermometer 11 comprising a stem 12 terminating at its upper end in an expansion chamber 13 and connected at its lower end to a bulb 14 containing an expandable fluid 15 present in such quantity that the expansion chamber 13 is not completely filled at the maximum temperature to which the thermometer may be subjected even during non-functioning of the refrigerator, and that during functioning of the refrigerator the top of the fluid column will lie in the vertical portion 16 of the stem 12 visible from the exterior of the refrigerator through the lens 17 secured in position by means of a split ring 18 in an annular depression 19 in a tube 20 extending through both the exterior sheet 21, the heat insulating material 22, and the interior sheet 23, of the refrigerator wall 24.

The thermometer 11 is supported in this position by means of a frame 25 comprising a pair of discs 26 and 27 each engaging snugly with the tube 20 and each provided with an aperture 28 or 29 adapted to snugly receive the expansion chamber 13 and an aperture 30 or 31 adapted to snugly receive the horizontal portion 32, the stem

12. In addition, the bulb 14 is supported on a bracket 33 projecting from the interior face of the plate 27, while the plates 26 and 27 are formed into a unit by means of struts 34 extending between and rigidly secured to the plates 26 and 27, and the entire frame 25 is secured in position within the tube 20 by means of an annular shoulder 35 on the tube 20 in position to be abutted by the outer face of the disc 26, and the spring ring 36 arranged to seat within the semi-circular recess 37 in the wall of the tube 20 and when so seated to abut the exterior face of the disc 27.

The joint between the lens 17 and the tube 20 is sealed by means of a packing disc 38 while the entire thermometer unit is protected from accidental injury by means of a plate 39 secured by means of screws 40 to the inner end of the tube 20 and provided with a multiplicity of perforations 41 arranged to afford free communication between the space about the bulb 14 and the space within the refrigerator.

It will be apparent from the above description that the thermometer unit herein shown may be readily inserted in a refrigerator by merely forming a hole through the wall 24 and inserting therein the tube 20, and the parts contained therein, and also that the thermometer may be readily removed by removing the protecting plate 40 and the split ring 18 and withdrawing the entire frame 25 from within the tube 20. It will also be apparent that while the thermometer is in its functioning position it will be entirely effective to indicate exteriorly of the refrigerator the temperature existing within the refrigerator, that because of the tight engagement of the lens 17 and discs 26 and 27 within the tube 20 the space within the tube 20 is divided into chambers arranged in series between the exterior and interior of the refrigerator and therefore effective to reduce and practically eliminate the entrance of heat through the tube 20 and thus prevent the decrease in efficiency which would result in that manner, and that the presence of the expansion chamber 13 prevents destruction of the thermometer at the relatively high temperatures to which the thermometer may be exposed during the periods over which the thermometer is not functioning. It will therefore be obvious

to those skilled in the art that the device herein shown and described accomplishes the principal object of my invention.

In addition, it will also be obvious to those skilled in the art that the particular embodiment of my invention herein shown may be variously changed and modified without departing from the spirit of my invention or sacrificing the advantages thereof. It will therefore be understood that this disclosure is illustrative only and that my invention is not limited thereto.

I claim:

1. In combination, a refrigerator wall provided with an aperture therethrough, a transparent closure closing the exterior end of said aperture, a thermometer, and a frame carrying said thermometer, comprising at least one plate arranged to close said aperture, and arranged to fit within said aperture with the bulb of said thermometer in communication with the space interiorly of said wall and the indicating portion of the stem of said thermometer disposed between said plate and said closure.

2. In combination, a refrigerator wall having a section comprising an outer transparent plate and an inner plate spaced therefrom, and a thermometer having its bulb disposed in communication with the space interiorly of said wall and its indicating portion disposed out of communication with said space and also out of communication with the space exteriorly of said wall, but positioned relative to said transparent plate to be visible therethrough from said space exteriorly of said wall, and connected to said bulb by a connecting stem extending from said bulb to said indicating portion through an aperture in said inner plate which is closed by said stem.

3. In combination, a refrigerator wall provided with an aperture therethrough, a thermometer, and a frame supported from the aperture surface of said wall, carrying said thermometer and arranged to fit within said aperture with the bulb of said thermometer in communication with the space in-

teriorly of said wall and with said frame and said thermometer essentially within the confines of said aperture.

4. In combination, a refrigerator wall provided with an aperture therethrough, a thermometer, and a frame carrying said thermometer, comprising at least one plate arranged to close said aperture, and arranged to fit within said aperture with the bulb of said thermometer in communication with the space interiorly of said wall and said plate and the indicating portion of the stem of said thermometer disposed exteriorly of said plate, and with said frame and said thermometer essentially within the confines of said aperture.

5. In combination, a refrigerator wall provided with an aperture therethrough, a thermometer, and a frame supported from the aperture surface of said wall, carrying said thermometer, comprising at least one plate arranged to close said aperture, and arranged to fit within said aperture with the bulb of said thermometer in communication with the space interiorly of said wall and said plate and the indicating portion of said stem disposed exteriorly of said plate, and with said frame and said thermometer essentially within the confines of said aperture.

6. In combination, a refrigerator wall provided with an aperture therethrough, a transparent closure closing the exterior end of said aperture, a thermometer, and a frame carrying said thermometer, comprising at least one plate arranged to close said aperture, and arranged to fit within said aperture with the bulb of said thermometer in communication with the space interiorly of said wall and the indicating portion of the stem of said thermometer disposed between said plate and said closure, and with said frame and said thermometer essentially within the confines of said aperture.

In testimony whereof, I hereunto affix my signature.

HADLEY F. FREEMAN.
